UNITED STATES PATENT OFFICE.

JOHN F. CHESTER, OF LOUISVILLE, KENTUCKY, ASSIGNOR OF THIRTY-FIVE ONE-HUNDREDTHS TO JOHN J. SEIBERZ, OF LOUISVILLE, KENTUCKY.

MAIL-BAG CATCHER.

No. 810,322.

Specification of Letters Patent.

Application filed July 3, 1905. Serial No. 268,154.

Patented Jan. 16, 1906.

To all whom it may concern:

Be it known that I, JOHN F. CHESTER, a citizen of the United States of America, residing at Louisville, in the county of Jefferson and State of Kentucky, have invented new and useful Improvements in Mail-Bag Catchers, of which the following is a specification.

This invention relates to mail-bag catchers, and has for its objects to produce a comparatively simple inexpensive device of this character in which the bag-supporting arms will normally stand and be automatically locked in an unobstructing position, one 15 wherein the arms may be readily reversed to accord with the direction of travel of the mail-car, and one in which the arms will be automatically locked in active position through engagement of the mail-bags there- 20 with.

With these and other objects in view the invention comprises the novel features of construction and combination of parts more fully hereinafter described.

25 In the accompanying drawings, Figure 1 is a side elevation showing the track and car cranes in active position for transferring the mail-bags from one to another. Fig. 2 is a front elevation of the car-crane. Fig. 3 is a 30 similar view of the track-crane. Fig. 4 is a detail perspective view of one of the bag-receiving arms. Fig. 5 is a similar view of the bearing for one of the arms and a portion of the latter.

35 Referring to the drawings, 1 designates the track-crane, comprising a pair of spaced posts or standards 2, attached at their lower ends to and arising vertically from the cross-ties, said standards, which are fixedly sustained 40 by braces 3, being connected at their upper ends through the medium of a transverse bar 4, bolted or otherwise secured in place, while carried by one of the standards is a platform 5, to which access may be had by a ladder 6.

45 Extending horizontally between and journaled in the standards at a point adjacent their upper ends is a shaft or axle 7, having rotatively mounted thereon a bearing member or casting 8, having at its outer end a pair of 50 oppositely-extending inclined recesses 9, communicating at their inner ends with and forming a continuation of a central bearing-opening 10, formed in the casting, said opening 10 being intersected by a transverse opening 11.

Carried by the casting 8 is a bag receiving and delivering member or fork 12, having a straight cylindrical portion or shank 13 extended through and mounted for rotation in the opening 10 and merging at its outer end into an inclined portion 14, adapted to seat 60 in one of the recesses 9, said portion 9 constituting one side of a substantially U-shaped bag-receiving opening or recess 15, the other side 16 of which is produced by suitably bending or shaping the material of which the fork 65 is composed. The fork is further provided with an outwardly and rearwardly projecting guide portion or arm 17, extending from the open mouth of the recess 15 and formed continuous with the side wall 16, which latter has formed thereon at a point adjacent 70 the inner end of the arm 17 a bag-engaging portion or finger 18, provided with a seat or recess 19. The portion 13 of the member 12 is equipped at its inner end with a head 20 75 and is provided between its ends with an opening 21, designed to register with the opening 11 for the reception of a coupling-pin 22, the head 20, which is removable from the shank, being maintained thereon by means of 80 a cotter-pin 23, entered through a suitable opening in the shank.

The standards 2 have extended therebetween at a point suitably remote from the ground a second horizontal shaft or axle 23, 85 on which is pivoted a lower bag-engaging member or arm 24, provided at its outer end with a pivoted bag-engaging portion or finger 25, adapted to swing in a horizontal plane and having formed in its lower face a seat or 90 recess 26, there being pivoted to the arm 24 at a point adjacent its inner pivoted end one end of a connecting element or rod 27, the other end of which is pivoted to the casting 8 at a point adjacent the inner pivoted end of 9 the latter, it being noted in this connection that the pivotal point 28 of the upper end of the rod 27 is a greater distance from the pivotal axis 7 of the casting 8 than is the pivotal point 29 of the lower end of the rod from the pivotal axis 23 of arm 24, and, further, that the rod 27 is provided with angular portions 30 and 31, disposed in relatively reverse directions in order to attain the proper dispositions of the pivots 28 and 29 relative to the pivots 7 and 23 for a purpose which will hereinafter appear.

Journaled in bearings 32, attached to the

door-frame 33 of the car, is a lower horizontal shaft or axle 34, having journaled thereon a bearing member or casting 35 identical in construction with the casting 8, above described, and carrying a bag-receiving member or fork 36, similar in all respects to the fork 12, except that the portion or shank 13 of fork 36 projects beyond the inner end of casting 35 and is equipped with a handle 37, the shank of the fork 36 being journaled in the casting 35 and normally fixed against rotary and also sliding movement by means of a pin 22, as in the corresponding construction above described.

15 Pivoted to the upper end of frame 33 by means of an eyebolt 38 is an upper bag-supporting arm 39, having a pivoted bag-engaging portion or finger 40 and connected with the casting 35 through the medium of a rigid element or link 41, said parts being all identical in construction and operation with the corresponding parts of the track-crane.

Disposed upon the shaft 7 at opposite ends of the casting 8 and between the latter and standards 2 are rubber cushioning members or buffers 42, corresponding buffers 43 being arranged upon shaft 34 between the casting 35 and sides of the door-frame, these buffers serving to sustain the shocks incident to engagement of the mail-bags by the forks.

15 In practice when the parts are arranged as in Fig. 1 for delivering mail to and receiving mail from the car the fork 12 of the track-crane will pass at a point centrally between the arm 39 and fork 36 of the car-crane, while the latter fork 36 will pass at a similar position between the fork 12 and arm 24, thus to adapt the respective forks for engagement centrally with the mail-bags 44 and 45. As 40 the bag 44 is received by fork 12 the finger 40 of arm 39 will swing freely on its pivot to bag-releasing position, it being apparent that the fork 36 will be positioned with its bag-engaging portion or finger 18 extended parallel 45 with the line of movement of the car, while at the same time the finger 26 of the arm 24 will also swing on its pivot for releasing the bag 45. In order to reverse the forks to accord with the direction of travel of the car, 50 the pins 22 are removed and the shanks 13 of the fork moved longitudinally outward through the castings until the inclined portions 14 of the forks are free from the recesses 9, whereupon the forks may be rotated and then moved inward, with the incline portion 14 seated in the other or opposite recess, after which the parts are again secured by means of the coupling-pins. When not in action, the parts normally stand in the unobstructing position illustrated in Figs. 2 and 3, but when moved to the position seen in Fig. 1 the arms and forks will be automatically locked through engagement of the mail-bags there-with and owing to the peculiar connection between the arm and fork of each pair, it being

noted that owing to the pivotal point 29 of the lower end of link 27 being nearer to the pivot 23 than is the pivot 28 to the pivot 7 the pivot 28 will swing in a greater arc of movement than pivot 29, and hence it becomes necessary for arm 24 to swing downward for permitting a similar swinging movement of casting 8. Therefore when the mail-bag 45 is in position it will serve to connect the casting and arm for simultaneous movement, thus acting through the rod or link 27 to lock the parts in horizontal bag-supporting position.

From the foregoing it is apparent that I produce a simple device admirably adapted 80 for the attainment of the ends in views, one in which the bag-supporting arms and engaging forks will be automatically locked in either active or inactive position, and one wherein the forks may be quickly reversed 85 when circumstances require, it being understood that in attaining these ends minor changes in the details herein set forth may be resorted to without departing from the spirit of the invention.

Having thus described the invention, what I claim is—

1. In a device of the class described, a support, a bearing member pivotally connected therewith and having an opening and a pair 95 of oppositely-disposed recesses communicating with said opening, a bag-receiving member having a shank journaled for rotation in and for movement longitudinally of the opening and an angular portion adapted to seat in either of the recesses, and a coupling-pin engaged through the bearing member and shank for fixing said shank against longitudinal movement.

2. In a device of the class described, a support, a bearing member pivotally connected therewith, a bag-engaging member journaled for rotation in the bearing member, interlocking connections between the members to prevent rotation of the engaging member, the latter being adapted for longitudinal movement to effect its release, and a coupling-pin entered through and for fixing the members against relative longitudinal movement.

3. In a device of the class described, a support, a bearing member pivotally connected therewith and provided with a recess, a bag-engaging member rotatively engaged with the bearing member and having a portion designed to seat in said recess, said engaging member being longitudinally movable relative to the bearing member for seating said portion in or unseating it from the recess, and a coupling-pin for fixing the parts against relative longitudinal movement.

JOHN F. CHESTER.

In presence of—

DANIEL J. HENNESSY,
WILLIAM D. CHESTER.
